United States Patent Office

Des. 208,429
Patented Aug. 29, 1967

208,429

NUT

Phillip G. Holliday, Bellwood, Ill., assignor to Standard Screw Company, Bellwood, Ill., a corporation of New Jersey

Filed May 12, 1966, Ser. No. 2,326

Term of patent 14 years

(Cl. D54—9)

FIGURE 1 is a side view of my design for a nut,
FIGURE 2 is a longitudinal section taken at line 2—2
of FIGURE 1,

FIGURE 3 is a top plan view,
FIGURE 4 is a bottom plan view, and

FIGURE 5 is a perspective looking in the direction
of the top of the nut.

I claim:

The ornamental design for a nut, as shown.
